UNITED STATES PATENT OFFICE

ALFRED EDWIN MCGRUER, OF TORONTO, ONTARIO, CANADA, ASSIGNOR TO HENRY EDWIN HALL AND WILLIAM JAMES DOBBIN, BOTH OF TORONTO, CANADA

ILLUMINATOR FOR WATER GAUGES

Application filed June 14, 1930. Serial No. 461,134.

The invention relates to improvements in illuminators for water gauges as described in the present specification and shown in the accompanying drawings.

- 5 The invention has for its object the production of a highly efficient and serviceable water gauge illuminator whereby the water level can be readily discerned even when the gauge is located at some distance above the eye of 55
 10 the tender, which is often the case in modern boiler installations. A further object is to provide an illuminator that is inexpensive to manufacture and easy to install on conventional water gauges.
 15 Referring to the drawings, Figure 1 is a side elevation of the invention fitted to a standard water gauge.

Figure 2 is a vertical section of the invention together with an elevation of the water 20 gauge, the major part of the fittings of which are broken away.

Figure 3 is a top plan view of the invention together with a section of the water gauge.

25 Figure 4 is a cross section taken on the line 4—4 of Figure 1.

Figure 5 is an elevation of an inner side of a supporting arm.

Figure 6 is a cross section thereof taken on 30 the line 6—6 of Figure 5.

Figure 7 is a cross section of the invention depicting a slightly modified form of casing.

Like numerals of reference indicate corresponding parts in each of the figures 35 throughout the drawings.

In the drawings, the water gauge exhibited consists of the usual water tube A held between the top fitting B and the lower fitting C, the rods D being provided as customary 40 to prevent breakage of the tube.

It is to be clearly understood that this style of water gauge is given by way of illustration but not of limitation as it will be apparent that the invention is not dependent upon the style of fittings or rods.

In carrying out this invention there is provided a casing 10 composed of the cylinder 11 and what may be termed a hood 12 which is preferably integrally constructed 50 as shown. The cylinder is spaced from the

water gauge and disposed parallel therewith, being located midway of the length of the water tube A. The cylinder is of a size sufficient to house a standard electric light bulb 13 lodged in the socket 14 and energized by the circuit 15 connected to a source of supply. The socket may be secured in any manner in an opening in the bottom of the cylinder, such as by means of the screw-thread 16; see Figure 2.

The bottom and the top of the cylinder are shown constituted of caps 17 and 18 in order that they may be detached to render the interior readily accessible. If so desired only one detachable cap need be employed so as 65 to provide for inserting and removing the bulb 13.

A vent 19 is supplied in the top portion of the cylinder and downwardly directed to preclude entry of water. By perforating the 70 cap 17, as at 19', air may enter the cylinder and circulate therein, escaping through the vent 19.

The cylinder has a vertical elongated opening from which the hood outwardly extends 75 to the glass tube A. The sides 20, 20, of said hood are parallel with each other and preferably of a width about equal to the diameter of the water tube. The edges 21, 21, are shaped to conform to the curvature of the 80 tube and contiguously engage it throughout their length, which is about equal to that of the tube between the fittings B and C. The top 22 and the bottom 23 of the hood diverge from the cylinder as shown. The inner surfaces 24 of these top and bottom portions are preferably polished so as to act as reflecting surfaces for rays emanating from the bulb 13 and falling upon these faces. The polished surfaces direct these rays onto the water 85 tube A and thus intensify its illumination.

The inner end of the hood is closed by a glass 25 held in place by any suitable expediency. This glass isolates the cylinder's interior from that of the hood so that should the water glass break, water or steam will be prevented from damaging the electric light. While it is proposed to use a plain glass for this purpose, it is conceived that a prismatic glass could be employed to advantage in order 95 100

to more uniformly diffuse the light rays upon the water tube.

From the preceding description of the invention it will be obvious that rays emanating from the bulb will pass through the hood and thus illuminate the water tube so as to clearly show the water level.

Various designs of devices could be employed to attach the illuminator to the water gauge, but that found most satisfactory in practice consists of a pair of arms 26, 26, which are connected to the rods D. Each arm consists of a plate 27 hinged at 28 to the cylinder in order to laterally swing. This swinging plate carries a slidable plate 29 having a pierced boss 30 through which the corresponding rod D is threaded. The slidable connection is obtained by opposing channels 31 in which the plate 29 is engaged, which plate is slotted as at 32 and the bolt 33 passed through it so that the nut 34 may clamp the two plates together in any position of adjustment. By this arrangement the arms may be swung to bring them into alignment, lengthened or shortened to bring their bosses into register with the rods.

In the modification shown in Figure 7, the casing is illustrated as of a pear-shaped configuration, consisting of an enlarged cylinder portion 35 from which the side walls 36, 36, of the hood 37 converge to the water tube. By polishing the interior surfaces of these side walls the light rays falling thereon may be directed to the water tube to aid in its illumination.

What I claim is:—

A water gauge illuminator composed of a casing having an elongated light emitting opening for lengthwise fitting against the water tube of the water gauge, a source of illumination contained in said casing, and supporting arms, said arms each consisting of a plate hinged to a side of the casing, a plate slidably carried in said hinged plate, a boss borne by said slidable plate for receiving a guard rod of the water gauge, a bolt lodged in a hole in one plate and in a slot in the other plate, and a nut threaded on said bolt for clamping said plates together.

Signed at Toronto, Ontario, Canada, the 30th day of May, 1930.

ALFRED EDWIN McGRUER.
